US0D1064741S

(12) United States Design Patent (10) Patent No.: US D1,064,741 S
(45) Date of Patent: * Mar. 4, 2025

(54) BOTTLE

(71) Applicant: Yinghai Hu, Yongkang (CN)

(72) Inventor: Yinghai Hu, Yongkang (CN)

() Term: 15 Years

(21) Appl. No.: 29/972,446

(22) Filed: Nov. 11, 2024

(30) Foreign Application Priority Data

Aug. 26, 2024 (CN) 202430540824.2

(51) LOC (15) Cl. 07-01

(52) U.S. Cl.

USPC D7/510; D7/608

(58) Field of Classification Search

USPC D7/392.1, 509, 510, 511, 521, 536, 407,

D7/523, 532, 400, 402, 300.2, 585, 608;

D3/202; D9/520, 532, 545

CPC A63F 2009/0058; A47G 19/2205; A47J

41/00; B65D 21/02

See application file for complete search history.

(57) CLAIM

The ornamental design for a bottle, as shown and described.

DESCRIPTION

FIG. 1 is a perspective view of my new design, showing a bottle;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The line shading in FIGS. 1-8 represents contour and not surface ornamentation.

1 Claim, 8 Drawing Sheets
